TROUSERS-CREASE MARKER.

1,273,555.

Specification of Letters Patent. Patented July 23, 1918.

Application filed June 1, 1917. Serial No. 172,141.

To all whom it may concern:

Be it known that I, ANDRÉ VARAUD, a citizen of France, residing at Geneva, Canton of Geneva, in the Confederation of Switzerland, have invented certain new and useful Improvements in Trousers-Crease Markers, of which the following is a specification.

The present invention relates to improvements in and relating to stretching devices adapted to maintain the original shape of certain parts of garments especially the creases of the legs of trousers during the use thereof.

15 This device consists in a resilient member or strip made for instance of celluloid, wood, whale-bone, steel spring blade or other suitable material adapted to be fixed under the turned up lower end portions of 20 trousers to mark, and assist in maintaining the creases therein.

The accompanying drawing illustrates by way of example several embodiments of the invention.

25 The Figures 1 to 7 relate to a device adapted to be fixed in the turned up portion of the lower part of the legs of trousers.

Figs. 1 and 2 show such a device formed 30 by the combination of two spring blades.

Fig. 3 shows a device formed by a single spring blade.

Fig. 4 is a view of a device formed by two movable spring blades.

35 Fig. 5 is a variation of the embodiment shown in Fig. 4, and

Figs. 6 and 7 are detail views showing the connection of the ends of two spring blades forming the device.

40 In all the embodiments of the invention shown in the drawings the part named spring-blade may be made of an elastic strip either of metal, or wood or celluloid, or whale-bone or other suitable material.

45 The embodiment shown in Fig. 1 comprises two spring-blades *a* and *b* the ends of which are connected together by clips *c* in order to form two projecting beaks designed to mark the front and back creases 50 of the bottom of trousers.

Each clip *c* is riveted at the end of one of the blades and adapted to engage by fric-

tion the end of the other blade and vice-versa.

In the embodiment shown in Fig. 2 the 55 blades *a* and *b* are combined with double clips *d* each forming an acute angle and engaging by friction the ends of the said blades *a* and *b*.

In the embodiment shown in Fig. 3, the 60 crease-fixing device comprises only a single spring blade *a*, which is bent so as to be U-shaped and to have its ends disposed in order to form between them a hinge *e* in which a pin *e*¹ is engaged for maintaining 65 the whole device in the form shown in the drawing. The hinge *e* is adapted to fix the front crease of the trousers.

This figure shows also that the spring blade may be covered by a material such as 70 canvas *f* to prevent its edges from wearing the cloth of the trousers.

The ends of the spring blades may be connected together by means of clips of different kinds and shapes, or by means of 75 rivets.

The device may also be made of two bent spring-blades, the one of which being U-shaped and the other V-shaped as shown in Figs. 4 and 5. These spring blades may be 80 connected together by means of clips *c* and *c*¹ (Fig. 4) fixed on the branches of one blade and into which the branches of the other blade are engaged. Or one of the blades may be provided with flat-headed 85 pins *p* each of which engages a slot *s* provided in the other blade. According to Fig. 6 the ends of the spring blades may also be connected by a flat headed pin *p*¹ provided on one end of the blade and engaging a slot *s*¹ in the other end of the blade, the end of the blade carrying the pin *p*¹ being bent over the end of the other blade provided with the slot *s*¹. 90

As shown in Fig. 7 one of the blades may 95 be provided near its end with a claw *g* which is engaged with a hole provided in the other blade also near its end and bent over, the end of one blade overlapping the end of the other in order to prevent a displacement of the blades relatively to each other. 100

The described device may be fixed in the crease of the lower part of trousers by any means whatever, for instance by introduc-

ing it into a loop sewed at the inside of the trousers.

The clips *c* of Fig. 1 and the clips *d* of Fig. 2 may replace the hinge *e* of the Fig. 5 3 and vice-versa.

Claims.

1. A trousers crease marker comprising a band of resilient material adapted to fit within the upturned lower end of a trouser leg and having a beak or pointed portion formed therein and adapted to mark a crease in the trouser leg. 10

2. A trousers crease marker comprising a pair of bands of resilient material adapted 15 to fit within the upturned lower end of a trouser leg and having oppositely disposed beaks or pointed portions formed therein adapted to mark creases in the trouser leg.

3. A trousers crease marker comprising a 20 pair of bands of resilient material adapted to fit within the upturned lower end of a

trouser leg and having oppositely disposed beaks or pointed portions formed therein adapted to mark creases in the trouser leg, and means for securing the said bands to 25 one another.

4. A trousers crease marker comprising bands of resilient material, and clips for connecting said bands of resilient material at the respective ends thereof so that these ends form beaks or pointed portions adapted to mark creases in the trouser leg, the said bands when thus connected being adapted to fit within the upturned end of a trouser leg for the purpose specified. 30 35

In testimony whereof I have affixed my signature in presence of two witnesses.

ANDRÉ VARAUD.
